UNITED STATES PATENT OFFICE.

TILLMAN CAHN, OF ELKINS PARK, PENNSYLVANIA, ASSIGNOR TO PIONEER SUS-PENDER COMPANY, A CORPORATION OF PENNSYLVANIA.

GARTER.

Application filed November 3, 1922. Serial No. 598,723.

To all whom it may concern:

Be it known that I, TILLMAN CAHN, a citizen of the United States, residing at Elkins Park, in the county of Montgomery, 5 State of Pennsylvania, have invented a new and useful Garter, of which the following is a specification.

My invention relates to improvements in garters. The object is to provide a construction 10 that will maintain the pad or connecting element flat and free from distortion, and at the same time preserve the feature that all metal parts are protected from contact with the leg, as required in devices of 15 this character.

Referring to the drawings which illustrate, merely by way of example, a suitable embodiment of the invention;

Fig. 1 is an elevation of a garter in the 20 unclasped or open position.

Fig. 2 is a fragmentary view showing the cast-off elements in engagement.

Fig. 3 is a section on the line 3, 3, of Fig. 1, only on an enlarged scale.

25 Similar numerals refer to similar parts throughout the several views.

The garter shown in the drawings and to which this invention is especially applicable, is of the wide web or wide leg band class.

30 This wide web construction has led to a change in the shape of the pad, which, instead of being horizontally wide and vertically narrow, as formerly, is now horizontally narrow and vertically wide. This 35 construction, in order to maintain the rustless character, has had the cast-off stud 12 fastened to the pad at substantially its middle part. This is usually the weakest part of the pad since the turned, or folded-in 40 portions of the several layers usually end near the inner line of stitching 7, and the result is a substantial distortion of the pad, after a short period of wear.

45 As stated in the preamble, the object of this invention is to maintain this pad "flat and free from distortion and at the same time preserve the feature that all metal parts are protected," etc. The leg band 5 is secured at one end to the connecting element 50 or pad 6, between the plies thereof, by the two lines of stitching 7. At its other end the leg band is provided with the cast-off element 8, in the usual way. At the lower 55 edge of the connecting element or pad 6, is secured the webbing 9 which carries the

stocking-clasp 10 in supported relationship with the connecting element 6. At the opposite margin of element 6, from that to which the leg band 5 is secured, are secured the two free ends of the short folded strip of webbing or other flexible material, forming the tab 11. This tab 11, which is preferably formed of the same webbing as that from which the leg band is formed, is secured in the same way between the plies forming the 60 element 6, by the two lines of stitching 7. The cast-off element 12 is secured to the element 6 by the stitching 13.

Now the important feature of this invention is the positioning of the element 12 70 and the tab 11, and the cooperation of these elements with the several folded plies of the element 6, and the stitching cooperating therewith.

In the formation of the connecting element or pad 6, it is usual to employ four layers or plies of fabric. The front layer or face 14 is usually of silk or other material of good quality matching or harmonizing with the fabric of the leg band 5. The back 75 layer or face 15 is of cheaper material, but of substantial body. Layer 14 is provided with a lining 16 and layer 15 is provided with a lining 17. These linings are of stiffening materials such as crinoline and duck. 80 Each layer or face and its lining are folded together, that is one over the other near the margin to form a hem. These two layers or faces, with their linings, are then secured together by the double line of stitching 7, after the leg band 5 and the tab 11 have been inserted as shown. The result is 85 that when the element 12 is positioned as shown in the drawings, and secured by the stitching 13, this stitching 13 passes through two extensions each, of face layers 14 and 15 and their respective linings 16 and 17, and also through the two layers 18 and 19 of the material forming the tab 11.

The result of this construction is, that 100 the stitching 13 passes, in the example shown, through 10 plies of material, including the comparatively heavy webbing of tab 11. These ten plies are re-enforced by the double line of stitching 7, which flank the 105 stitching 13. In this way an extremely firm and substantial base is provided upon which to secure the element 12, so that the tendency to cause distortion of the connecting element or pad 6, by the pull on element 12, 110

is reduced to a minimum. At the same time the tab 11 forms a shield or protection, preventing the metal of the cast-off elements from touching the leg.

5. What I claim is:—

In a wide web garter, the combination of a leg band, a connecting pad having its vertical extension greater than its horizontal extension and formed of a plurality of pairs 10 of layers of fabric, each pair of layers folded together at their margins, the leg band secured to one side margin of the pad, and

having at its free end a cast-off element, a tab formed of folded webbing having its two ends inserted between the said pairs of 15 folded layers at the other side margin of the pad, with lines of stitching securing said webbing ends and said layers together, and a cast-off element secured to the pad near its last mentioned side margin by stitching 20 passing through said pairs of layers and their folded-in portions and said webbing ends.

TILLMAN CAHN.
